UNITED STATES PATENT OFFICE.

ALBERT H. DE VOE, OF WESTFIELD, NEW JERSEY, ASSIGNOR TO THE SINGER MANUFACTURING COMPANY, A CORPORATION OF NEW JERSEY.

POWER-TABLE.

1,320,455.

Specification of Letters Patent.

Patented Nov. 4, 1919.

Application filed April 19, 1916. Serial No. 92,257.

To all whom it may concern:

Be it known that I, ALBERT H. DE VOE, a citizen of the United States, residing at Westfield, in the county of Union and State of New Jersey, have invented certain new and useful Improvements in Power-Tables, of which the following is a specification, reference being had therein to the accompanying drawings.

10 This invention has for its object to provide a power-table particularly adapted for small light-running machines, such as sewing machines, which shall be inexpensive in construction, which shall have the requisite rigidity, which may be readily disassembled for shipment and as readily assembled for installation, and which shall provide effective means of support and easy adjustment in all requisite directions 15 for power-transmitters for driving the machines sustained by the table.

The present improvement is preferably embodied in either a single or a double power-table of the well-known Singer type, such as those of the United States patents, J. A. Reid, No. 678,978, of July 23, 1901, or H. Corrall, No. 1,147,377, of July 20, 1915, and is directed specially to a particularly advantageous construction 20 of the frame-work sustaining the top-boards which serve as supports for the machines to be driven. The table-top is usually constructed in sections extending lengthwise of the power-shaft and comprises preferably two parallel series of end-to-end top-boards with an intermediate space occupied by a flat tray or a trough to receive the finished or unfinished work.

In its preferred form, the table comprises two parallel series of top-boards arranged end-to-end with the joints between the boards of each series in substantial alinement with similar joints between the boards of the other series, supports being 25 arranged at intervals between such joints and the ends of the extreme boards consisting of upright standards disposed in alinement transversely to the top-boards and formed with alined transverse heads having flat tops to afford supporting faces for the abutting ends of the boards. The heads of the standards are preferably formed in their adjacent end portions with alined open-ended sockets entered by the opposite ends of connecting bars which are secured

adjustably in said sockets to thereby produce endwise adjustable transverse frame-members.

Secured upon the lower faces of the top-boards adjacent their ends are reinforce 60 plates which are preferably provided with reversely inclined and apertured seats upon which are seated the heads of fastening bolts passing through their apertures and similar apertures in correspondingly inclined seats formed upon the heads of the standards, upon which are seated nuts applied to said bolts for drawing the connected parts together independently of the connections between the reinforce plates and the top-boards. At the abutting ends of the top-boards the fastening bolts are oppositely inclined and in transverse relation with each other so as to draw the reinforce 65 plates flatwise upon the supporting faces of the standards and edgewise toward each other so as to form a rigid structure and avoid the production of open joints or seams between the abutted ends of the boards.

One of the reinforce plates of each adjacent pair is preferably provided with a segmental seat extending crosswise of the table to which is fitted the correspondingly shaped foot of a hanger having a similar and substantially vertical segmental seat to which is fitted the adjacent part of a power-transmitter frame containing rotary power-transmitting elements disposed concentrically with the longitudinally extending power-shaft with which one of said members has a driving connection.

The hanger is adjustably secured upon the segmental seat of its respective reinforce plate, and the power-transmitting frame is similarly secured upon the segmental seat of the hanger by means of axially extending bolt-and-slot connections of such character that the transmitter can be adjusted bodily toward and from and parallel with the face of the top-boards transversely of said shaft and also angularly upon axes both intersecting and parallel with the top-boards. Thus ample means are provided for readily and accurately lining up the power-shaft 95 which is in practice supported at intervals by the table-frame by means of the power-transmitters to which it communicates the power for driving the machines upon the table.

110

The reinforce plates of the present improvement serve as battens to strengthen the top-boards and prevent warping and distortion; and they are so secured to the standards that the strains imposed in securing them firmly in position thereon are received only by the frame-members excepting in the endwise thrust of the abutted top-boards which is such as to close the joints between them and thereby exclude introduction of small objects, such as pins or needles, the projection of whose points would be liable to injure the hands of the operators. The mounting of the transmitter-frames upon the reinforce plates independently of the supporting standards permits of the described accurate alinement of the transmitters of a series and the power-shaft connecting them without the usual precision of installation of the standards, and allows of the initial erection of the table with its top properly leveled regardless of the lining up of the power-shaft and the transmitters, which may be more easily performed thereafter without disturbing the larger and heavier parts of the structure.

The invention will be understood by reference to the accompanying drawings, in which Figure 1 is a side elevation of a part 30 of a power-table installation, and Fig. 2 a view of the under side of the same with a portion of the intermediate work-supporting section removed. Fig. 3 is a view, partly in transverse section and upon an enlarged scale, showing the head of one of the standards and its connection with the top-boards and also one of the transmitter-supporting hangers, and Fig. 4 is a sectional elevation of the same on the line 4—4 35 of Fig. 3. Fig. 4^a is a sectional view showing the manner of securing a single reinforce plate to a standard at the end of a top board. Fig. 5 is a view of the under side of the abutted ends of two top-boards with their respective reinforce plates. Fig. 6 is a top plan view of the head of one of the standards. Fig. 7 is an enlarged perspective view of one of the treadles for operating the power-transmitters.

50 As represented in the drawings, the table-top comprises parallel series of end-to-end disposed machine-sustaining top-boards 1 which are rabbeted along their lower inner edges to receive the edges of the intermediate work-supporting boards 2. To the lower faces of adjacent top-boards near their abutting ends are secured by fastening screws 3 the transverse reinforce-plates 4 and 5, respectively, slightly spaced apart, 55 the plate 4 being somewhat wider than the latter. The adjacent marginal portions of the plates 4 and 5 are formed upon their lower faces with depending lugs 6 above and extending into which are cavities 7 laterally 60 open at 8 at the side of said lugs beneath the

plates and having downwardly and backwardly inclined bottoms 9 affording flat seats through which extend laterally open slots 10 communicating with the cavities 7 and passing entirely through the lugs 6. 70 The lugs 6 of each plate are laterally offset with respect to those of the other plate, as represented particularly in Fig. 5.

The wider reinforce-plate 4 is formed adjacent its edge opposite the lugs 6 with depending seats comprising the lengthwise and crosswise spaced bearing faces 11 in segmental arrangement, those upon one side being inclined inwardly and upwardly reversely to those at the other side of each 80 seat. Intermediate the similarly inclined bearing faces of each seat, an elongated aperture 12 is formed in the body of the plate beneath which is a depending lug 13 having a slot 14 open at one end whose edges 85 overhang the aperture 12.

Each of the supporting standards for the table-top comprises a post 15 adapted to be secured to the floor by bolts 16 and having a flattened upper portion 17 formed with a 90 vertical slot 18. Adjustably secured to the upper portion 17 of the post by bolts 19 passing through the slot 18 is the longitudinally apertured shank 20 of the cross-member or head 21 of the standard which is provided at the upper side with oppositely extending spaced lugs 22 affording supporting faces to receive the depending ribs 6' of the reinforce-plates 4 and 5 adjacent the lugs 6. 100

The lugs 22 are spaced apart sufficiently upon one side of the member 21 to embrace the lugs 6 of the plates 4 and 5, and upon the opposite side of such member are so spaced apart as to form an open slot 23 of 10 substantially the width of the slots 10, and having their side faces downwardly and inwardly inclined to afford seats 24 corresponding in inclination with the seats 9 of the lugs 6 opposite the same. Passing through the registering slots 10 and 23 are clamp-bolts 25 having their heads 26 resting upon the seats 9 of the lugs 6 and provided upon their threaded opposite end portions with nuts 27 between which and the seats 24 of the lugs 22 are interposed the washers 28.

As the adjacent portions of seats 9 and 24 for the heads and nuts of the fastening bolts are inclined in opposite directions relatively to the line of division between the abutted 12 ends of the top-boards, it will be observed that such bolts are disposed in crossed arrangement and that each exerts a thrust which is opposed to that of the other along the supporting face of the head 21 of the 13 standard. Between the adjacent ends of the top-boards 1 is preferably interposed a packing strip 29 of soft material, such as felt, to insure that there shall be no open seam or crack at such point.

The reinforce-plates having been previously secured to their respective top-boards and the component parts of the standards having been secured together, two abutting 5 top-boards are placed upon the head of a standard with the bearing flanges 6' resting upon the supporting faces of the lugs 22. The fastening bolts 25 are then introduced, their heads 26 being passed through the 10 lateral openings 8 of the lugs 6, after which the nuts and washers are applied. As the nuts are screwed up to draw the seats 9 toward the seats 24, the reinforce-plates 4 and 5 are forced toward each other upon and 15 along the flat supporting faces of the bearing lugs 22, thereby thrusting the ends of the top-boards against each other or against the interposed packing and serving to clamp all three members firmly together to produce a structure of the utmost rigidity. The 20 construction is such that, after continued use in which the parts may work loose to some extent, any lost motion between them may be readily taken up by merely turning 25 the nuts 27 so as to not only clamp the reinforce-plates more firmly upon the standards, but simultaneously draw the respective top-boards together to close the joint between them.

30 To secure the outer extremities of the end top-boards upon their respective standards, two of the narrower reinforce-plates 5 may be secured thereon with the edge of each adjacent that of the other, in the manner 35 shown in Fig. 5, their lugs 6 being staggered in arrangement to receive the head 21 of the standard which is secured thereto by bolts 25 as previously described. In case it should be desired to use only a single plate 5, 40 the head of the standard may be constructed as represented in Fig. 4^a with the extremities of the lugs 22 at one side preferably cut off and these lugs at the same time extended upwardly slightly to afford stop-shoulders 45 22' against which the edge of the reinforce-plate is abutted by tightening of the bolts 25.

According to the present improvement, 50 the reinforce-plates serve as battens to prevent the warping or other distortion of the top-boards to which they are secured, in addition to their function as elements of the fastening means by which the table-top is attached to the heads of the standards. As 55 the clamping force is applied to such plates edgewise, there is no appreciable tendency to wrench them from the attached top-boards, and the parts may therefore be clamped together with the necessary force 60 without any liability to injury or disarrangement of the parts.

Each of the cross-members 21 is provided 65 with an inwardly projecting extension 21' having a slightly raised seat 30 to sustain the marginal portion of the intermediate

board 2 (Figs. 2 and 3) to which it is secured by fastening screws 31. The extension 21' is formed with an open-ended socket extending lengthwise thereof and divided into spaced sections 32 by transverse slots producing lateral recesses at intervals in the length of the socket to afford thrust-sustaining shoulders 33 in the member 21' below the bore of the socket. The member 21' is formed with clearance apertures 34 passing through the seats 33 in which are introduced the set-screws 35 externally screw-threaded to receive the nuts 36.

Within the sockets of the aligned and transversely disposed top-board supporting members 21 of each pair are introduced the opposite ends of a tie-bar 37 which is adjustably secured in position by means of the set-screws 35 whose points bear upon said bar with their nuts bearing upon the thrust-shoulders 33 (Fig. 3). By the construction described, standards of a given size and pattern are adapted for tables of different widths, while the standards are readily packed in small compass for shipment and as readily assembled in installing the power-table.

Fitted upon the segmental seats 11 of the reinforce-plates 4 are the convergently inclined marginal portions 38 of the foot 39 of a depending hanger 40, the foot 39 being shown with flattened upper and lower faces and formed in the opposite ends with open slots 41 adapted to loosely embrace the shanks of clamp-bolts 42 passing through the slots 14 of the lugs 13 with their heads 43 disposed in the clearance apertures 12 and resting upon the marginal portions of the lugs 13. Nuts 44 are applied to the bolts 42 for clamping the foot 39 in position, the construction being such that the hanger may be laterally tilted slightly upon the axis of the segmental seat or may be adjusted bodily lengthwise of said axis.

The body portion of the hanger is provided in one face with vertical concave segmental seats 45 similar to the seats 11 of the reinforce-plates and with elongated apertures 46 intermediate the convergently disposed portions of such seats.

Each of the hangers 40 sustains a power-transmitter comprising operative rotary elements housed within a casing 47 which is formed upon one side with segmental projections 48 fitted to the seats 45 to which they are adjustably secured by means of tap-bolts 49 passing loosely through the slots 46 of the hanger and tapped into the power-transmitter casing, washers 50 being preferably interposed between the heads of the bolts 49 and the apertured member of the hanger. By the means described, the transmitter-casing is adapted to be adjusted circularly upon the axis of curvature of the segmental seats 45 and bodily lengthwise of

said axis. The hanger thus provides both angular horizontal and bodily vertical adjustment for the rotating parts of the transmitter in respect of their axes of movement, 5 while the described mounting of the hanger upon the reinforce-plate provides both angular vertical and bodily horizontal adjustment for such parts, the bodily adjustments being parallel to the respective axes of circular adjustment and transverse to each other.

As represented in the drawings, the transmitters are constructed each with a friction clutch-disk 51 secured upon the power-shaft 15 52 and in practice formed with a conical face engaging a corresponding cavity of the loose peripherally grooved belt-wheel 53 to which is connected the peripherally grooved belt-pulley 54 in a manner well known. The belt 20 pulley 54 is embraced by a driving belt 55 extending through a slot 56 in the top-board 1 and surrounding the pulley 57 fixed to the balance-wheel 58 of one of the sewing machines 59 to be driven.

25 The clutch-member 51 may be pressed into operative engagement with the clutch-member 53 by any suitable or usual means, that represented herein being a bent lever 60 mounted upon the fulcrum-pin 61 sustained 30 by the casing 47 and carrying an inclined cam-plate 62 engaging a thrust-pin 63 which has a connection with the clutch-member 51. The lever 60 has rigidly connected therewith the brake-arm 64 which is in practice provided with a brake-shoe for arresting the 35 motion of the brake-pulley 53. Each lever 60 is shown connected with the upper end of a sectional treadle-rod 65 having in its lower end a hook 66.

40 The transverse member of the hook 66 rests in a groove 67 formed in an upwardly extending lug 68 of a lateral ear 69 formed upon the treadle-plate 70 which is provided with the trunnions 71. The hook 66 at the 45 lower end of the treadle-rod 65 is confined within its groove of the lug 68 by means of an arched heavy-wire clip 72 resting upon the top of the lug 68 and having its divergent limbs passed down through slots upon 50 opposite sides of said lug in the ear 69 (Fig. 7).

The trunnions 71 of the treadle-plate rest in transverse cavities 73 in the upper ends of the stands 74 having the feet 75 secured 55 to the floor by means of screws 76'. The upwardly and convergently inclined edges of the stands 74 are preferably formed with grooves 77, and the trunnion nearest the treadle-rod connection is preferably confined 60 within its bearing cavity, by means of an inverted U-shaped clip 78 whose divergent limbs rest in the groove 77 of its respective stand 74, its extremities extending into the suitably elongated aperture for the head of 65 the fastening screw 76' and turned out-

wardly for engagement by the under side of the screw-head whereby the clip is securely fastened in position.

From the foregoing description and the accompanying drawings, it will be observed 70 that the frame-work of the power-table is constructed of a number of parts all of which, with the exception of certain connections in the form of screw-bolts and rods, may be constructed as metal castings 75 which are so formed as to be susceptible of the requisite fit without the employment of machine work thereon; and hence their construction is comparatively inexpensive, although affording means for very accurate 80 adjustment, which is highly important to insure the perfect alinement of the power-shaft from one to the other end of the power-table. The treadle device, which forms a part of the power-table outfit, is 85 similarly adapted to employment of castings without special fitting.

While the present improvement is shown and described herein in what is deemed the best and most advantageous embodiment, it 90 is evident that it is susceptible of material modification within the scope of the invention to correspond with different conditions under which the table may be designed for use.

Having thus set forth the nature of the invention, what I claim herein is:—

1. A power-table comprising a standard provided with a supporting face, a top-board, a reinforce plate secured upon the 100 face of said board parallel with said supporting face of the standard, adjustable clamping means acting at an inclination to the supporting face of said standard to draw said plate edgewise and flatwise upon 105 said standard, and means for receiving the edgewise thrust of said plate imposed by said clamping means.

2. A power-table comprising a standard provided with a supporting face and with 110 apertured seats inclined thereto, a top-board, a reinforce plate secured upon the face of said board parallel with said supporting face of the standard and provided with apertured seats inclined correspondingly with 115 those of said standard, and headed bolts fitted with nuts and entering the apertures of said plate and the standard and having their heads and nuts in engagement with the respective seats.

3. A power-table comprising a standard provided with a supporting face, a plurality of top-boards arranged end-to-end, reinforce plates secured upon the faces of and at the adjacent ends of said boards, and adjustable 125 clamping means acting at an inclination to said supporting face of the standard to draw said plates edgewise toward each other and flatwise upon the supporting face of said standard.

4. A power-table comprising a standard provided with a supporting face, a plurality of top-boards arranged end-to-end, reinforce plates secured upon the faces of and at the 5 adjacent ends of said boards, and bolts extending crosswise of each other and inclined to said supporting face of the standard and each acting to draw its respective reinforce plate upon and lengthwise of said supporting face to force the top-boards together endwise.
5. A power-table comprising a standard provided with a supporting face and with apertured seats inclined thereto in opposite 15 directions, a plurality of top-boards arranged end-to-end, reinforce plates secured upon the faces of adjacent ends of said boards and provided with reversely inclined and apertured seats, and headed bolts fitted with 20 nuts and entering the apertures of correspondingly inclined seats of said plates and standard and having their heads and nuts in engagement with the respective seats apertured to receive them.
- 25 6. A power-table comprising a top-board, a pair of standards spaced apart and disposed transversely thereof and provided with transversely arranged heads having supporting faces and open-ended sockets extending lengthwise thereof, reinforce plates 30 secured to the face of said top-board and each resting upon and secured to the supporting face of one of said standards, and a connecting bar with its opposite ends entering the sockets of the heads of said standards in which it is adjustably secured.
- 35 7. A power-table comprising a top-board, a pair of standards spaced apart and disposed transversely thereof and provided 40 with transversely arranged heads having open-ended sockets extending lengthwise thereof and formed with lateral recesses to afford thrust-shoulders exterior to the bore of said sockets, means for securing the heads of said standards to said top-board, a connecting bar with its opposite ends entering 45 the sockets of the heads of said standards, and set-screws provided with nuts interposed between said bar and said thrust-shoulders by means of which the bar is secured in position.
8. A power-table comprising a standard provided with a supporting face, a plurality of top-boards arranged end-to-end, batten-plates secured upon the lower faces of and 50 at adjacent ends of said boards, a plurality of tension members for securing contiguous batten-plates upon a supporting face of a standard, said plates and standard being shaped so that tightening of a tension member 55 moves a plate both endwise and flatwise to draw the ends of the top-boards together and hold them down.
9. In a power-table having a work-supporting portion, supporting leg members, 60 one or more tie members for maintaining the leg members fixed in spaced relation, and means independent of said members for fixedly connecting them together comprising a pair of relatively rotatable wedge-like elements arranged between parts of said members.
10. In a power-table having a work supporting portion, supporting leg members, 65 one or more tie members for maintaining certain of said leg members fixed in spaced relation, and means separate from said members for fixedly connecting them together comprising an inter-connected nut and screw, one of which bears against a leg member 70 and the other against a tie-member.
- In testimony whereof, I have signed my name to this specification.
- ALBERT H. DE VOE.
